Filed Apr. 7, 1958, Ser. No. 726,859

Claims priority, application Germany Apr. 11, 1957

2 Claims. (Cl. 80—38)

The present invention relates broadly to the art of metal rolling.

More particularly, this invention relates to a rolling mill installation of the type set forth in my prior application Serial No. 708,790, filed January 14, 1958, entitled "Rolling Mill."

The present invention, which may be considered an improvement of the structure disclosed in the said copending application, relates to a rolling mill of the type equipped with a plurality of working rolls and intermediate rolls revolving about stationary roll supporting means, the mill being characterized by the fact that those elements which, while also revolving about the supporting means, keep the rolls spaced from one another and with parallel axes, are at the same time constructed to serve as the means for transmitting the driving forces to the rolls, each working roll being supported by two intermediate rolls, each intermediate roll consisting of a plurality of roll sections arranged serially in axial direction, and of connecting elements disposed between these sections so as to hold the same at a predetermined spacing from one another. Each of the intermediate roll sections consists of an outer ring and an inner ring, the inner rings being fixed to axles non-rotatably mounted on the roller cages and being provided with peripheral surfaces disposed some concentric with and some eccentric relative to the central axis of the respective axle.

In such a rolling mill, each pair of intermediate rolls is swingable as a unit about the axis of the corresponding working roll, as a result of which the intermediate rolls, during their movement about the roll supporting means, are able to adapt themselves to the form of predetermined guide elements which are arranged on the roll supporting means or bodies and cause the peripheral surfaces of the latter to depart from a purely circular configuration. Such a swinging movement of the intermediate rolls, however, always entails a displacement of the same either in or opposite to the direction of the rolling operation, which is a condition readily seen to be inimical to the attainment of a satisfactory supporting of the working rolls and uniform roll pressure transmission.

It is, therefore, an important object of the present invention to provide means in a rolling mill construction capable of avoiding this drawback. To this end, according to the invention, the pairs of intermediate rolls are journaled by means of trunnions in circular sector-shaped slide elements which engage in recesses of suitable bearing members by means of flanges, collars or like extensions, the bearing members supporting the respective slide elements on suitable bearing surfaces for swinging movement about the axes of the associated working rolls.

Another highly important object of the present invention is the provision of means, in a rolling mill having the aforesaid structure incorporated therein, for constraining the working rolls to rectilinear movement radially of the respective roller cages regardless of the swinging or angular movements executed by the said slide elements and the intermediate rolls supported thereby.

A further object of the present invention is the provision of means cooperating with the roller cages, the bearing members, the slide elements and the various rolls for biasing the working and intermediate rolls into constant engagement with each other and for ensuring constant engagement between the bearing members and the corresponding slide elements.

The foregoing and other objects and characteristics of the present invention will be more fully understood from the following detailed description thereof when taken in conjunction with the accompanying drawing, in which:

Fig. 1 is a vertical section through the rolling mill constructed in accordance with the principles of the present invention;

Fig. 2 is a side elevational view, on an enlarged scale, of a working roll and one of the associated intermediate rolls, the bearing structure therefor being shown in section; and

Fig. 3 is an elevational view taken in the direction of the arrow X in Fig. 2, certain parts being broken away or omitted for the sake of clarity.

Fig. 4 is an end view showing the assemblage of a pair of intermediate rolls, the corresponding working roll being shown diagrammatically;

Fig. 5 is a plan view of the assemblage of Fig. 4;

Fig. 6 is a partial section taken on line 6—6 of Fig. 5.

Referring now more particularly to the drawing, it will be seen that the roll-shaped supporting bodies 20 and 21 are disposed one above the other and are non-rotatably mounted in mill stands 32. About and in rolling contact with these supporting bodies are arranged, respectively, pairs of intermediate rolls 25—25' and 26—26' each supporting a respective one of the working rolls 16 and 17 and disposed at uniform angular intervals from one another, for revolving movement about the supporting bodies 20 and 21 in the directions of the arrows 18 during performance of a rolling operation by means of the working rolls 16 and 17. The intermediate rolls are constructed of sets of alternately wider and narrower, axially serially arranged roll sections each consisting of an inner ring fixed to the non-rotatable roll axle, and an outer ring rotatably encircling the said inner ring, the peripheral surfaces of some of the inner rings being concentric with their respective axle, and the peripheral surfaces of the remaining inner rings being eccentric with respect to their respective axle, all as seen in Figures 4, 5 and 6 and as fully disclosed in the aforesaid copending application.

On the adjacent or facing sides of the supporting bodies 20 and 21 are provided guide elements 23 and 24 which define converging surfaces 23' and 24', as well as parallel surfaces 23" and 24". The peripheral surface of each supporting body thus departs from a purely circular configuration at both sides of these guide elements, whereby these peripheral surfaces define both diverging and converging paths.

The supporting bodies 20 and 21 are surrounded by rotatably and drivably journaled roller cages 34 and 35 in which the working rolls are mounted through the intermediary of slide blocks 111 and 112 arranged for radial displacement in the roller cages. The slide blocks serve as bearing means for the working rolls 16 and 17 as well as for the intermediate rolls 25—25' and 26—26' (see Fig. 2). Inasmuch as the movements of the slide blocks are always rectilinearly radial of the roller cages, the generation of lateral forces tending to produce undesired shifting or displacement of the working rolls during a rolling operation is completely avoided.

As seen in Figs. 4, 5 and 6, the intermediate rolls are mounted on axles 100, which are held in parallel relationship by spacers 114 and 115, one at each end of the rollers, and by spacers 108 placed between adjacent

roller elements 101 and 102. The intermediate rolls each comprise an axle 100 on which are mounted two sets of roller elements 101 and 102 which are eccentric to each other. From Fig. 5 it will be noted that in each pair of intermediate rolls the roller elements 101 of one roll are located opposite roller elements 102 of the other roll.

As seen in Figs. 4 and 6, the eccentricity of the roller elements 101 is toward the supporting body 23 or 24 and the eccentricity of the roller elements 102 is toward the working roll 16 or 17.

Spacers 108 between the roller elements are appropriately shaped and, as seen in Figs. 5 and 6, one set of roller elements may be narrower than the other set of roller elements.

Fig. 6 shows one means by which the eccentricity of the roller elements may be accomplished. Roller elements 101 are mounted on a bearing race 105 and bearing elements 103 are provided to make a low friction bearing between race 105 and roller element 101. Bearing race 105 is non-rotatably mounted concentrically on axle 100. Roller elements 102 are mounted on bearing races 106 and bearing elements 104 are provided between races 106 and roller elements 102. Race element 106 is non-rotatably and eccentrically mounted on axle 100 so that the surface of roller elements 102 will support the working roll for free rotation and the surfaces of roller elements 101 will support the axles 100 and therefore roller elements 102 in spaced relationship to the supporting bodies 20, 23 and 21, 24.

In order to secure a constant engagement between the working rolls and the respective pairs of intermediate rolls, as well as between the latter and the supporting bodies, pressure means are provided between each slide block and the respective roller cage. As shown in Fig. 3 with respect to blocks 111 and cage 34, such pressure means advantageously may comprise a plurality of compression springs 113.

For the purpose of facilitating rolling of the intermediate rolls 25-25' and 26-26' over the acircularly contoured surfaces of the guide elements 23 and 24, each pair of intermediate rolls, considered as a unit, is journaled for swinging movement about the axis of the associated working roll. To this end, the terminal sections or end plates 114 and 115 of the intermediate roll pairs, which interconnect their axles with one another substantially as set forth in the above-mentioned copending application, are provided with trunnions or like extensions 114' and 115' which are journaled in circular sector-shaped slide elements 116 and 117, respectively. The latter, being seated on arcuate bearing surfaces which are concentric with the axes of the associated working rolls and formed in bearing members or bodies 118 and 119, can thus move angularly about the axes of the associated working rolls. The slide elements 116 and 117 are provided with flanges or collars 116' and 117' which extend into and ride in arcuate guide recesses provided at the facing sides of the bearing bodies 118 and 119 (see Figs. 2 and 3), whereby axial displacement of the intermediate rolls is inhibited. The bearing bodies are kept in engagement with the slide elements by means of compression springs 120 and 121.

From the foregoing it will be understood that a construction according to the present invention will substantially eliminate any possibility of undesired lateral shifting of any of the working rolls 16 and 17 during contact of the associated intermediate rolls 25-25' and 26-26' with the guide elements 23 and 24, respectively. Stated in other words, any angular movement of a pair of intermediate rolls as a unit relative to and about the axis of the associated working roll can result only in a linear displacement of the said working roll radially of the particular roller cage in which it is mounted, whereby true bilateral vertical alignment of each two active work-

ing rolls during contact thereof with the rolling stock is assured at all times.

Various changes in and modifications of the structure and structural arrangements disclosed hereinabove may, of course, be made without departing from the spirit and scope of the present invention, and it is intended that such changes and modifications be embraced in the appended claims.

Having thus particularly described the invention, what is claimed and desired to be protected by Letters Patent is:

1. In a rolling mill equipped with a pair of stationary roll supporting bodies, annular and drivable roller cages mounted for rotation about said supporting bodies, respectively, a plurality of axially parallel working rolls mounted in each roller cage for revolving movement therewith about the respective supporting body, a plurality of pairs of axially parallel intermediate rolls mounted in each roller cage for revolving movement therewith about and in rolling contact with the respective supporting body, each of said intermediate roll pairs supporting on the side thereof remote from the associated supporting body a respective one of said working rolls, each intermediate roll comprising a plurality of axially serially arranged roll sections and a plurality of connecting elements located, respectively, between said roll sections to maintain the same at a predetermined spacing relative to one another, each of said roll sections comprising a non-rotatable inner ring and an outer ring rotatably encircling the same, the peripheral surfaces of some of said inner rings of each intermediate roll being concentric with their common axis, and the peripheral surfaces of the remaining inner rings of each intermediate roll being eccentric with respect to their common axis; the improvement comprising a plurality of slide blocks carried by each of said roller cages for rectilinear radial displacement thereon, said working rolls being journaled in said slide blocks, pressure means interposed between said slide blocks and said roller cages and biasing said slide blocks in a direction tending to maintain constant rolling contact between said working rolls and the corresponding pairs of intermediate rolls, a bearing member mounted in each of said slide blocks and each said bearing member being provided with an arcuate bearing surface and an arcuate guide recess, a plurality of circular sector-shaped slide elements carried, respectively, by said bearing members on said bearing surfaces thereof and each provided with a flange engaging in the corresponding guide recess, each of said intermediate roll pairs being provided at each of its opposite ends with a trunnion journaled in the associated slide element, and spring means interposed between said bearing members and said slide blocks and biasing said bearing members to press said intermediate roll pairs against said working rolls, whereby said slide elements and said intermediate roll pairs are mounted for angular movement about the respective axes of the associated working rolls.
2. In a rolling mill equipped with a pair of stationary roll supporting bodies, a plurality of axially parallel working rolls mounted for revolving movement about said supporting bodies, respectively, a plurality of intermediate rolls mounted in pairs and in axially parallel relationship for revolving movement about and in rolling contact with said supporting bodies, respectively, each of said intermediate roll pairs supporting on the side thereof remote from the associated supporting body a respective one of said working rolls, each intermediate roll comprising two sets of alternating, mutually eccentric, axially serially arranged roll sections and a plurality of connecting elements located, respectively, between adjacent ones of said roll sections to maintain the same at predetermined spacings relative to one another; the improvement comprising a plurality of slide blocks carried

by each of said roller cages for rectilinear radial displacement thereon, said working rolls being journaled in said slide blocks, a bearing member mounted on each said slide block each said bearing member being provided with an arcuate bearing surface and an arcuate guide recess, a plurality of sector-shaped slide elements each carried by a respective one of said bearing members on said bearing surface thereof and each provided with an extension engaging in the corresponding guide recess, and each of said intermediate roll pairs being provided at

5

each of its opposite ends with a trunnion journaled in the associated slide element, whereby said slide elements and said intermediate roll pairs are mounted for angular movement about the respective axes of the associated working rolls.
